UNITED STATES PATENT OFFICE

LEO H. UNDERWOOD, OF WALHONDING, OHIO

CAN AND JAR WRENCH

Application filed March 12, 1931. Serial No. 522,044.

This invention relates to an improved can and jar wrench and one object of the invention is to provide a device of this character by means of which a can or jar may be very firmly held while a screw top is removed, it being understood that if so desired one of the implements may be used for holding the jar or can and another engaged with the top so that both the receptacle and the top may be firmly gripped and sufficient leverage applied to cause the top to be easily unscrewed.

Another object of the invention is to so construct the wrench that a flexible band forming part of the same may be adjusted to accommodate itself to the jar or top about which it is to be disposed and also cause the band to be tightened about the jar or top.

Another object of the invention is to provide the wrench with a handle so constructed that the flexible jar encircling strap may be passed through the handle and move longitudinally through the same in order to fit tightly about a jar and to further permit the band to be firmly held in an adjusted position after being drawn about the jar and prevented from slipping while removing the top of the jar.

Another object of the invention is to provide a device of this character which is simple in construction, easy to adjust and very efficient in its operation.

The invention is illustrated in the accompanying drawing wherein:

Figure 1 is a perspective view of the device,

Figure 2 is a longitudinal sectional view through the same, and

Figure 3 is a transverse sectional view taken along the line 3-3 of Figure 1.

The handle 1 of this improved implement is preferably formed of strong sheet metal, although other materials found suitable may be used. The handle is in the form of a flat tube of sufficient length to be easily grasped in one hand, and in order to reinforce end portions of the tube constituting the handle there have been provided rings 2 formed of strong wire and conforming to the contour of the tube.

These rings are disposed about the ends

of the tube and portions of the walls are rolled about the rings as shown at 3. This is clearly shown in Figure 2. Therefore the ends of the handle will be strengthened and also rough edges will be eliminated which would be liable to cut the strap 4 and weaken it when the device is in use. If so desired the rings may be omitted and ends of the walls turned under to eliminate rough edges.

This strap 4 may be formed of any flexible material found suitable such as leather or woven fabric of the type used for belts, but woven fabric is preferably employed as it is strong and at the same time flexible. One end of the strap has applied thereto a mounting 5 formed of a strip of sheet metal folded intermediate its length and secured in straddling relation to the strap by rivets 6. This mounting projects from the strap and is loosely engaged with an eye or ring 7 carried by a clip 8 also formed of sheet metal and welded or otherwise firmly secured against the handle 1 in spaced relation to the forward end thereof. The free end of the strap is passed rearwardly through the handle and is then folded back upon itself and passed through a retainer 9 secured about the handle in spaced relation to the rear end thereof. It will thus be seen that by drawing the strap rearwardly through the handle or sliding it forwardly through the same, the diameter of the loop 10 formed by the forward portion of the strap may be regulated and the loop engaged about a jar or cap and drawn tightly about the same.

After the loop has been tightened about a jar or its cap, the free end of the strap is drawn forwardly through the retainer 9 and the strap will be prevented from slipping forwardly through the handle. The handle may then be swung in a direction to move the mounting 5 towards the handle and this will tend to reduce the diameter of the loop 10 and cause the loop to be drawn very tightly about the jar or its cap and a jar encircled by the loop may be very firmly held while a cap is unscrewed. The cap may be unscrewed either by grasping it in one hand or by applying a second implement to the cap in case a cap is screwed very tightly into place and

leverage is necessary in order to unscrew it.

While it has been stated that the device is to be used for removing caps from jars and cans, it will be obvious that it may be used for screwing a top tightly into place or for tightening or loosening pipe joints or for other purposes where it is necessary to hold one object stationary while another is screwed into or out of engagement with it.

- 10 In order to prevent any danger of the strap slipping forwardly through the handle after the loop 10 has been adjusted about a jar, there has been provided a latch 11 which extends longitudinally of the handle intermediate of its length and is mounted on an axle at 12, said axle being securely fastened to the handle either by soldering as shown at 13 or in any other manner desired. The latch is provided with a bill 14 which engages the strap 4 through an opening 15 formed in the handle. This bill is located close to the axle and of such length that it will pass under the axle when the end 16 of the latch is moved away from the handle. When said latch has 25 its end 16 moved to extend at an angle of 90° with the handle, it is clear that it will leave the strap free for adjustment, but when it is forced downwardly again, the bill engages the strap and is held securely by the pressure 30 from the other side of the handle.

This bill may be provided with teeth and is intended to bite into the strap. Since it is disposed at an incline as shown in Figure 2 strain applied when the device is in use will 35 cause the latch to more firmly grip the strap.

What is claimed is:

1. A wrench comprising a handle consisting of a flat open ended tube having an opening in one side wall thereof and communicating 40 with the interior of the tube, the other side wall of the tube being imperforate, a yoke projecting from the other side of the tube and spaced from said opening, a strip of flexible material having one end connected 45 with said handle in spaced relation to the front end thereof, said strip being extended rearwardly through said handle to form a loop at its forward portion normally and permanently disposed wholly on one side of the handle and having its rear end projecting 50 from the rear end of the handle and folded upon itself and passed through the yoke to form a second loop normally disposed wholly on the other side of the handle, a pin extending 55 transversely across the opening in the tube, and a clamping member pivotally mounted on said pin and provided with a bill extending through the opening in the tube for engagement with the strip of flexible material at a point opposite the imperforate side 60 wall of the tube.

2. A wrench comprising a handle consisting of a flat tube open at its opposite ends, a strip of pliable material having an end connected with one side of the handle in spaced 65

relation to the front end thereof, said strip being extended rearwardly through the handle to form a loop at its forward portion normally disposed wholly on one side of the handle and having its rear end projecting from the rear end of the handle and loosely connected therewith to form a loop normally disposed on the other side of said handle, and means to retain the strip in adjusted position after being moved through the handle. 75

3. A wrench comprising a handle consisting of a flat tube open at its opposite ends and provided with terminal laterally curved portions, and a strip of flexible material having an end connected with said handle in spaced relation to the front end thereof, a yoke carried by the handle near its rear end, said strip being extended rearwardly through said handle to form a loop at its forward portion normally and permanently disposed wholly on one side of the handle and its rear end projecting from the rear end of the handle and passed through the yoke to form a loop normally disposed on the other side of said handle whereby the rear end of the strip may be gripped by a hand grasping the handle and the strip held in adjusted position after being moved through the handle to adjust the size of its loop. 85

4. A wrench comprising a handle consisting of a flat open ended tube, a yoke carried by one end of the tube, a strip of relatively stiff flexible material extending through said handle, reinforcing rings fitted about the ends of the tube, the walls of the tube having their ends rolled about portions of the rings to hold the rings in place and form rounded ends for said walls, one end of said strip being loosely connected to the handle in spaced relation to the front end thereof and forming an article-encircling loop normally and permanently disposed entirely on one side of the handle, the other end of said strip being extended through the rear end of the tube and said yoke to form a loop normally disposed on the other side of said handle, and means to engage the rear portion of said strip and retain the same in a set position after being moved through the handle to adjust the size of its loop. 100 105 110 115

In testimony whereof I affix my signature.
LEO H. UNDERWOOD. [L. s.]
